WRAPPING OR PACKAGING DEVICE

Joseph L. Meyer, Dubuque, Iowa, assignor, by
mesne assignments, to Saf-T-Pop Corporation,
Dubuque, Iowa, a corporation of Delaware

Application April 22, 1935, Serial No. 17,642

6 Claims. (Cl. 99—180)

This invention relates to a wrapping or packaging device primarily for edibles of the type wherein the edible is equipped with a handle of loop-like configuration which is usually, but not necessarily, non-rigid. That class of edibles includes candies, frozen ices, ice creams, and other edibles which are or may be so equipped with handles.

An object of the invention is the provision of a novel packaging device or wrapper for such edibles.

Another object of the invention is the provision of a simply constructed yet effective device for packaging or wrapping a plurality of solidified edibles for sale and display as a unit, and which is readily operable for unpacking to facilitate the sale of the edibles one at a time.

A further object of the invention is the provision of such a packaging device or wrapper which facilitates releasably binding together a plurality of edibles, which will hold them together in shipping units or sub-units sufficiently securely as to protect the individual edibles, and which does not interfere with the characteristics of the edibles adapting them for display purposes but which in fact improves the display characteristics thereof.

Other objects of the invention include the provision of the combinations and arrangements of elements hereinafter disclosed and claimed, as illustrated in the accompanying sheet of drawings wherein the reference numerals respectively refer to the same elements throughout the several views, and in which:

Figure 1 is a perspective view of a group of edibles embraced by a packaging device or wrapper embodying the features of the invention;

Figure 2 is a plan view of the packaging device or wrapper of the invention in a stage of its development; and

Figure 3 is a perspective view of the novel packaging device or wrapper alone.

Illustrative of the invention, a plurality of edibles or suckers 11, each including an edible portion of, for example, candy that may be enclosed by a wrapper 12, and a handle portion 13 are bound together by a novel packing device or wrapper 14, as shown in Figure 1. The handle portion 13 of each sucker preferably is non-rigid and includes adjacently arranged portions 15 extending into the candy and an intermediate portion 16 connecting the portions 15 and forming a loop-like configuration.

The novel wrapper 14 is constructed of cardboard, paper, or other suitable packaging material, and has a base or supporting portion 17 of sufficient length to span the thickness of an edible

portion or the combined thicknesses of the edible portions of the suckers 11. This base portion 17 is connected at each end to side or display portions 18 and 19. If desired, the portions 18 and 19 may be integral with the portion 17, and the side portions may be provided by folding the integral strip along fold lines 21 and 22.

The side portion 18 has a length greater than the length of the wrapped candy, and at the end opposite the fold line 21 it is provided with a tab 10 22 having a slot 23 extending longitudinally of the side portion 18 and a transverse slot 24 connecting with and extending across the end of the slot 23. Likewise, the side portion 19 is of greater length than the length of the wrapped candy, and at its end opposite the fold line 22 it is connected with an aligning member 25 by a hinge portion 26.

The member 25 has at its free end an attaching enlargement or head 27 providing a shoulder or abutment 28 and receivable in the vertical slot 23. 20 When the head 27 is inserted in the slot 23 the shoulder 28 is adapted to engage the tab 22 above the slot 24 for releasably holding the packaging device closed. It is preferred to make the aligning member and hinge portion from a reduced 25 portion 29 integral with the side portion 19.

To that end the reduced portion 29 is provided with a generally rectangular aperture 31 which terminates short of the free end of the portion 29 in substantially a straight edge 30 and at its other end has an arcuate portion 32. The aperture 31, with the arcuate portion 32 thereof, cooperates with a fold line 33 extending from the free end of the reduced portion 29 longitudinally thereof to the straight edge 30, with transverse fold lines 34 in the reduced portion 29 at opposite sides of the aperture 31 near the arcuate portion 32, and with angularly disposed fold lines 35 diverging from the arcuate end 32 of the aperture 31 toward the respective edges of the side portion 19, whereby to permit folding the reduced portion 29 along its longitudinal center line and to render it swingable about the hinge provided by the fold lines 34 and 35 to and from a position substantially at right angles to the face of the side portion 19.

It will be seen that when the reduced portion 29 is so folded, the fold line 33 and the straight edge 30 define the latching shoulder or abutment 28, and the fold lines 34 and 35 produce the hinge portion 26, which, by virtue of the folds and the resiliency of the material from which the novel packaging device or wrapper is made, will tend to urge the alignment member 25 up toward the upper end of the vertical slot 23, where the shoulder 28 will engage behind the 55

tab 22 above the transverse slot 24 for holding the packaging device or wrapper closed.

In use, a sucker or suckers 11 are placed with the ends of the edibles opposite the handles 13 against the base portion 17, and the side portions 18 and 19 are folded up along the outer faces of the edible or edibles. The suckers and packaging device or wrapper are held in that relative position while the aligning member 25 is inserted 10 through the loop handle or loop handles 13 and is drawn down about the hinge portion 26 to a position between the adjacent portions 15. The head 27 is then inserted into the longitudinal slot 23 until the shoulder 28 is at the outside surface 15 of the side portion 18, and the aligning member 25 is moved upward about the hinge portion 26 until the shoulder 28, engaging the outer surface of the tab 22 above the transverse slot 24, secures the packaging device or wrapper about 20 the edible or edibles. The resilient character of the hinge portion 26 will tend to hold the aligning member 25 in the last described position.

Thus the packaging device or wrapper not only provides valuable advertising space on the side portions 18 and 19 but also provides a unitary package for edibles with loop handles, which package is self-supporting on the base portion 19 and which does not interfere with the display characteristics of the loop handles.

30 While I have illustrated and described a preferred embodiment of my invention, many modifications may be made without departing from the spirit of the invention, and I do not wish to be limited to the precise details set forth but 35 desire to avail myself of all changes within the scope of the appended claims.

I claim:

1. A wrapper for edibles with handles, comprising a wrapper strip of a length sufficient to extend about four sides of an edible, said strip including coacting fastening means at opposite ends thereof for releasably securing it in wrapping position, and means intermediate the ends of said strip for urging a fastening means 40 toward securing relationship with the other said fastening means comprising a hinge having an angularly disposed fold with respect to a transverse line across the wrapper and a transverse fold.

50 2. A wrapper for edibles with handles, comprising a pair of spaced side portions, another portion connecting corresponding ends of said side portions, a said side portion having an elongated aperture therein at the end thereof

opposite said other portion, and a connecting portion connected at one end to the end of the other said side portion opposite the second said portion, said connecting portion being folded upon itself to provide a stiffened fastening member of a width less than the length of said elongated aperture removably receivable in said aperture for releasably securing said connecting portion in connecting relationship between said side portions.

3. A wrapper for edibles having loop handles, comprising a base portion, side portions, releasable means connecting said side portions at the ends opposite the base portion, and means on one side portion for urging said releasable connecting means toward continued locking engagement with said other side portion, said connecting means extending through the loop portions of said handles to hold the edible in interlocking engagement with the side and base portions of the wrapper.

4. A wrapper for a handle carrying edible comprising a pair of spaced side portions connected at corresponding ends to a base portion, an elongated aperture in the end of one side portion opposite the base portion and coacting fastening means connected to one side portion and extending to the elongated aperture in the other side portion for releasable locking engagement therewith, said coacting fastening means extending through the loop handle of the edible for interlockably holding the edible in the wrapper on four sides thereof.

5. A packaging device for edibles comprising a strip adapted to be wrapped around one or more of the edibles, one end of said strip being provided with a latch receiving and engaging recess and the other end with a portion folded along a longitudinal line upon itself to provide a stiffened latch member for engagement with said recess.

6. A packaging device for edibles comprising a strip adapted to be wrapped around one or more of the edibles, one end of said strip being provided with a latch receiving and engaging recess and the other end with a portion folded along a longitudinal line upon itself to provide a stiffened latch member for engagement with said recess, and a resiliency imparting fold at the junction of the rear of the latch member and the adjacent portion of the strip which urges said stiffened latch member in a direction which tends to retain the same in latching position within said recess.

JOSEPH L. MEYER.
